DESIGN FOR A CARD FOLLOWER BLOCK FOR A FILING DRAWER

Hugh B. Johnson, Rochester, N. Y.

Application August 29, 1942, Serial No. 108,072

Term of patent 3½ years

To all whom it may concern:

Be it known that I, Hugh B. Johnson, an employee of the United States Government, a citizen of the United States, residing at Rochester, New York, have invented a new, original, and ornamental Design for a Card Follower Block for a Filing Drawer, of which the following is a specification, reference being had to the accompanying drawing, forming part thereof.

Fig. 1 is a perspective view of a card follower block for a filing drawer, showing my new design;

Fig. 2 is a front elevational view; and
Fig. 3 is an end elevational view thereof.

I claim:

The ornamental design for a card follower block for a filing drawer, as shown.

HUGH B. JOHNSON.
